UNITED STATES PATENT OFFICE.

AGNES E. VAN KIRK, OF NEW YORK, N. Y.

COMBINED ARTIST'S CASE AND EASEL.

SPECIFICATION forming part of Letters Patent No. 259,441, dated June 13, 1882.

Application filed May 3, 1881. (No model.)

To all whom it may concern:

Be it known that I, AGNES E. VAN KIRK, of the city of New York, in the county and State of New York, have invented a new and useful 5 Combined Artist's Case and Easel; and I do hereby declare the following to be a full, clear, concise, and exact description of my invention, such as will enable others skilled in the art to which it appertains to make and use the same, 10 reference being had to the accompanying drawings, which form part of this specification.

The object of my invention is to make a case for artists, which is also in the nature of a table, having several compartments to hold the 15 palettes, paint-box, sponge, glass or tin water-cup, pencils, brushes, and other articles used by artists while sketching or painting. The case is so arranged that it may be attached to any easel and used as a table, which may be 20 adjusted in any position desired by an artist while sketching or painting, or it may be detached from the easel, and when closed will form a box to contain the sketcher's materials, and may be carried with ease by him during 25 sketching expeditions, and will also be useful to the artist as both table and case at home.

Figure 1 shows the artist's case when closed, except the drawer B, which is drawn partly out. Fig. 2 is a perspective top view of the 30 case when the lid A is removed. Fig. 3 is a direct end view, looking at the end into which the drawer B slides. Fig. 4 is a sectional view of one side of an easel, showing a dovetailed groove, i, in a metal strip, I, which is inserted 35 in the side of the easel. Fig. 5 shows metal rests f' f', which may be used in the aperture D shown in Fig. 2 for the purpose of holding a water-glass. Fig. 6 shows a slotted strip of metal, I, made in suitable form to be attached 40 to the standards of an easel, and forming with it a groove, i, for the purpose of receiving and permitting the dovetailed metal slide k shown in Figs. 7 and 8 to slide up and down. Fig. 45 7 is a sectional view of the table and easel when attached to each other in the manner hereinafter described. Fig. 8 is a horizontal sectional view of the table and easel, showing the forked dovetailed metal slide h and the manner in which it is hinged to the dovetailed 50 metal slide k. Fig. 9 is a view showing the un-

der side of the table when attached and adjusted to the easel K.

The ordinary size of the artist's case is two and one-half feet in length and one foot in width and about one and three-quarter inch 55 in depth, although it may be made of any desired size. The material for making it should be cherry or other hard wood, which will make a fine finish and not be too heavy to be carried with ease. The thickness of the wood for the 60 cover, ends, and bottom need not be more than one-quarter or three-eighths of an inch; but the back piece should be thicker and made very strong.

The lid A (shown in Fig. 1) should be made 65 so that the ends will slide into the grooves c c. (Shown in Fig. 2.) The lid may be secured by the hooks a a, which catch into the eyes g g.

The board C (shown in Fig. 2) is to be used for the purpose of holding the paint-box and 70 pallets, and I will therefore designate it as the "color-board." It is divided into spaces or sections F F by the dovetailed slats E E, which are made to fit and slide into the dovetailed grooves e e extending across the color-board; 75 but if it should be found best to make the color-board very thin, on account of weight in carrying the case, it may be made in several parts, with spaces sufficient for the slats E E to slip 80 between them, and the ends of the slats may 85 rest upon the supports for the color-board or slide into grooves made in such supports. The slats E E should be wide enough to come above the color-board about one-quarter or one-half of an inch, so as to prevent the paint-box, &c., 90 from slipping off the table or out of their position. The grooves e e are made so that some 95 of the slats will run straight and others diagonally across the color-board. The distance between the straight divisions is four inches and between the diagonal divisions two and one-half inches; but any number of grooves may be made to receive the slats E E; and at any desired distance apart, and as the slats are movable they can be adjusted so as to accommodate a paint-box of any size. The space F' in the left-hand corner may be used for the sponge. For the purpose of holding the water-glass, an aperture, D, is made through the color-board, and light leather straps f f may 100

be fastened at each end to the color-board, so that they will form a loop which will drop to a distance of three or four inches. These loops, being deeper than an ordinary painter's glass, 5 will in case of jogging allow the water to run to the ground instead of over the color-board and materials. If there should be danger of knocking the glass while sitting at work, the metal rests $f' f'$, (shown in Fig. 5,) being rigid, 10 may be used instead of the leather straps. There are also eyes at the end of the table, which are made to receive the catch (three-quarters of an inch in width) on tin water-cups, when they are preferred to a glass.

15 Directly in front of the color-board a trough, G, about one inch in width and one-half of an inch in depth, is made for the purpose of containing the brushes, pencils, &c., to be used by the artist while at work.

20 At one end of the case is a drawer, B, which slides in under the color-board, and which is made wide enough to occupy the space between the back of the case and the opening D. The drawer may be fastened by the button on the 25 inner end of the knob b, or in any other suitable manner. This drawer will hold the slats E E when they are removed from the color-board, and such other articles as may be desired.

30 On the back of the table a dovetailed groove, H, should be made by letting a metal strip having a groove in it into the wood, so that its outer edge will be even with the edge of the wood, or by attaching a slotted metal strip to 35 the wood. This strip of metal should be made very strong and be firmly attached to the wood, as it will bear nearly the whole weight of the table; but, if necessary, straps similar to the straps of a trunk-lid may be used to aid 40 in supporting the weight. The groove H should extend from one end to the other, so that when attached to an easel the table may be made to slide laterally.

45 As shown in Fig. 4, a metal strip, I, having in it a dovetailed groove, i, may be inserted in the standards of the easel; but where the holes in an old easel should not leave space enough for this a slotted metal strip, I, (shown in Fig. 6,) may be attached to the standards 50 of the easel, forming the groove i, as shown in Fig. 9, the object of the groove or slot i being to permit the table, when attached to an easel, to slide up or down, so that it can be adjusted at any desired height.

55 For the purpose of attaching and adjusting the table to an easel, two dovetailed metal slides, h and k, (shown in Figs. 7 and 8,) may be used. The metal slide h is forked, as shown in Fig. 8, and is hinged to the slide k by means 60 of the bolt l'. The fork of the metal slide h also passes on each side of a perforated adjusting-arc, P, and has in it a hole to permit the pin l' to pass through the forks and through the holes in the adjusting-arc P, to secure the table so 65 that it may always be horizontal, no matter what may be the angle of the easel. The metal

slide k extends downward an inch or more, so as to permit a thumb-nut, j, or thumb-screws to be used for the purpose of securing the table when placed at the desired height. The 70 slides k being in the grooves i i on each standard of the easel, the table is attached to it simply by placing it so that the projecting metal slides h will slip into the groove H at the end of the table, and then on across until 75 the projecting slide h on the opposite standard has also slipped into the groove H. The table can then be adjusted at any desired height by loosening the thumb-nuts j j or thumb-screws and sliding it up or down, as the 80 case may be, and then securing it by tightening the thumb-screws.

An easel being of a triangular form, the metal slides h and k, by which the table is attached to it, must necessarily approach each 85 other as the table is moved upward, and will separate as it is lowered. The groove H extending across the back of the table will allow the slides to approach or move from each other, according to the movement of the table 90 up or down. The lateral and vertical motions are very important, as they enable the artist to adjust the table to suit either a standing or sitting position; and as the slats E E in the color-board are movable and run at different 95 angles, the paint-box and the palettes can be placed where and in the position in which they are needed. There being also a small space between the table and the easel, the ordinary pegs may be dispensed with, as the sketching-block can rest upon the adjusting-arcs and 100 will be braced by the back of the table.

As the case can be securely closed and fastened, it may be used as a "carry-all" for the sketcher by merely attaching a handle for 105 the purpose of carrying it, and thus be made especially useful for outdoor work. It is arranged more particularly for water-colors, but may also be used in oil-painting.

Having thus described my invention, what I 110 claim as new, and desire to secure by Letters Patent, is—

1. An artist's case adapted to be adjustably attached to an easel, consisting of the color-board C, the trough G, and drawer B, substantially as described, and for the purpose set forth.

2. In combination with an easel, the color-board C, divided into spaces by the removable slats E E for the purpose of supporting 120 the painting materials, substantially as described.

3. The combination of the color-board C, having dovetailed parallel grooves, and the adjustable slats E E, dovetailed to fit said 125 grooves, dividing the board into sections, and longitudinally removable, substantially as described.

4. The combination of an easel and a case or board for supporting painting materials, 130 the board being adjustable laterally and vertically, substantially as described.

5. In combination with an easel having the grooves *i i* and slide *k*, an artist's case having the groove *H* and the slide *h*, the slides being connected to enable a lateral and vertical adjustment of the case, substantially as and for the purpose set forth.
6. The combination of the dovetailed grooves *i i* in an easel and the slides *h h*, having the thumb-screws *jj* for securing an artist's case or board at any desired height, substantially as described.
7. An artist's case consisting of the color-board *C*, trough *G*, drawer *B*, and lid *A*, which, when closed, will hold the painting materials and may be carried.

AGNES E. VAN KIRK.
